(57) CLAIM

The ornamental design for a money clip, substantially as shown and described.

DESCRIPTION

FIG. 1 is a front elevational view of a money clip showing my new design:

FIG. 2 is a left side view thereof;

FIG. 3 is a rear view thereof;

FIG. 4 is a right side view thereof; and,

FIG. 5 is a perspective view thereof.

The broken lines are for illustrative purposes only and form no part of the claimed design.

1 Claim, 5 Drawing Sheets

FIG. 1## FIG. 2

FIG. 3FIG. 4*FIG. 5
